UNITED STATES PATENT OFFICE.

CLAUDE RORABECK, OF DAYTON, OHIO.

AIR-COMPRESSOR.

1,162,884.

Specification of Letters Patent.

Patented Dec. 7, 1915.

Application filed January 2, 1915. Serial No. 129.

To all whom it may concern:

Be it known that I, CLAUDE RORABECK, a citizen of the United States, residing at Dayton, in the county of Montgomery and 5 State of Ohio, have invented certain new and useful Improvements in Air-Compressors; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in air-compressors of a type adapted to be used in connection with light explosive engines, such as are used for propelling motor boats.

20 The object of the invention is to provide a device of this type which is simple in construction, safe and efficient in operation and in which the excess pressure generated is cared for in a simple manner.

25 Referring to the accompanying drawings, Figure 1 is a longitudinal vertical section through the cylinder of the compressor; Fig. 2 is a section on the line *a—a* of Fig. 1; Fig. 3 is a section on the line *b—b* of 30 Fig. 1.

In the specification and drawings, similar reference characters designate corresponding parts both in the description and drawings.

35 Referring more particularly to the drawings, 1 represents an air-compressor cylinder provided with a face 2 by means of which said air-compressor may be conveniently attached to any suitable support.

40 Mounted within said cylinder 1 is a compressor piston 3 which is provided with packing-rings 4 and is connected with an eccentric or crank (not shown) by a connecting rod 5 in a well known manner.

45 The connecting rod 5 is coupled to the piston by a wrist-pin 6 and the piston 3 is further provided with oil grooves 7 which are well known lubricating means. The oil for lubricating the piston is supplied there- 50 to through a port 8. The cylinder is further provided with air inlet ports 9 which are exposed when the piston 3 reaches the lower end of its stroke, the said piston

drawing a partial vacuum during its suc- 55 tion stroke. During the upward movement of said piston, the air in the cylinder previously drawn in through ports 9 is com- pressed in the upper end thereof beneath the cylinder head 10 and is discharged from said cylinder through a cylindrical valve 60 11 mounted in a boss 12 and provided with an exhaust pipe 13. The seating end of said valve 11 is of conical form and co- operates with a correspondingly formed seat. The said valve is under the control 65 of a spring 14 the tension of which may be regulated by a cap 15 mounted in the boss 12. The pipe 13 leads to a suitable reservoir (not shown) and when the pres- 70 sure in the reservoir becomes excessive or when the pipe 13 is shut off, the air com- pressed in the cylinder 1 is discharged past a relief valve 16 of similar construction. The valve 16 is mounted in a boss 17 in the cylinder head 10 and is provided with a 75 discharge port 18 which is open to the atmosphere. The said relief valve is further provided with a spring 19 the tension of which may be adjusted by a cap 20 mounted in the upper end of the boss 17. The air- 80 compressor so constructed and arranged is simple and efficient and reduces to a minimum trouble experienced with the handling of the air under compression. It further eliminates the possibility of injury or break- 85 age of parts due to overpressure.

Having described my invention, I claim.

In an air compressor, the combination of a cylinder having air intake ports in the side of the compression end thereof, and a piston 90 coöperating therewith, of a solid casting mounted on the compression end of said cylinder and forming the head thereof, said head having two uniform openings extending vertically therethrough and having in- 95 ternal threads in the outer ends thereof and terminating at their inner ends in valve seats which communicate with the compres- sion end of the cylinder, and lateral dis- charge openings extending from said seats 100 through the sides of said head, a tubular valve mounted in each of said vertical open- 105 ings below the internal threads thereof, said valves controlling the discharge of air from the cylinder at different pressures, a spring mounted in each valve and normally con-

trolling the seating action thereof, and adjustable caps closing said openings above the valves and forming the outer abutments for the springs and serving to regulate the tension of the springs so that a greater pressure is required to open one of said valves than the other.

Copies of this patent may be obtained for five cents each, by addressing the "Commissioner of Patents, Washington, D. C."

In testimony whereof I affix my signature, in presence of two witnesses.

CLAUDE RORABECK.
